ELECTRIC-CABLE ATTACHING DEVICE

Peter M. Petrie, New Haven, Conn., assignor to
The Rattan Manufacturing Company, New
Haven, Conn., a corporation of Connecticut

Application September 28, 1936, Serial No. 102,859

7 Claims. (Cl. 285—6.5)

This invention relates to an improvement in attaching devices and particularly to devices for attaching electric cable to junction-boxes, outlet-boxes, etc.

5 One of the objects of the present invention is to provide a simple, reliable and effective electric-cable attaching device having a wide range of use, and economical to manufacture.

A further object is to provide a superior electric-cable attaching device characterized by its capacity for securely attaching electric cables of varying sizes to an outlet-box, junction-box, or other electrical device.

With the above and other objects in view, as will appear to those skilled in the art from the present disclosure, this invention includes all features in the said disclosure which are novel over the prior art.

In the accompanying drawing:

20 Fig. 1 is an outer-end view of one form which an attaching device embodying the present invention may assume;

Fig. 2 is a view thereof in side elevation;

Fig. 3 is a view similar to Fig. 2 but looking 25 toward the diametrically opposite side of the device;

Fig. 4 is a transverse sectional view taken on the line 4—4 of Fig. 1;

Fig. 5 is a transverse sectional view taken on 30 the line 5—5 of Fig. 1;

Fig. 6 is an end view corresponding to Fig. 1 but showing the clamping-member reversed for clamping a cable of relatively-small size;

Fig. 7 is a view of the outer end of the clamping-member detached;

Fig. 8 is a view of one face of the clamping-member; and

Fig. 9 is a view of the opposite face of the clamping-member.

40 The electric-cable attaching device herein chosen for illustration comprises in the main a body-member, generally designated by the numeral 10, and a clamping-member, generally designated by the numeral 11. The body-member

45 10 includes an externally-threaded tubular stem 12, a polygonal wrench-receiving portion 13, and an upstanding clamping-portion 14 having its central portion substantially conforming to the curvature of the fitting and provided with two 50 outwardly-extending ears 15—15, each of which is provided with a threaded perforation 16 for the reception of one of two clamping-screws 17—17.

The reversible clamping-member 11 is placed in opposition to the clamping-portion 14 of the body-member 10 and is provided with two oppo-

sitely-offsetting ears 18—18, one of which is provided with a cylindrical perforation 19, and the other of which is provided with a notch 20 (Figs. 3 and 8). The clamping-screws 17—17, before referred to, respectively extend through the perforation 19 and the notch 20 in the reversible clamping-member 11 and into the threaded perforations 16—16 in the clamping-portion 14 of the body-member, and serve to draw the said reversible clamping-member and the said clamping-portion toward each other to clamp an electric cable therebetween.

The reversible clamping-member 11 is formed in one face with a notch-like cable-receiving recess or socket 21 of relatively-large size and radius, and is formed in its opposite face at the terminus of an offsetting-lug 22, with a notch-like cable-receiving recess or socket 23 of relatively-small size and radius as compared to the said recess 21. Extending across the recess 21 of the clamping-member 11 is a gripping-rib 24, which is preferably inclined with respect to the general plane of the clamping-member 11, as shown in Fig. 8, to substantially conform to the helix angle of the covering of metal-covered electric cables. The recess 23 of the reversible clamping-member 11 is also provided with a gripping-rib 25 for the purpose of enabling the said clamping-member 11 to more firmly grip a relatively-small size electric cable, as shown in Fig. 6.

The threaded stem 12 of the body-member 10 is adapted to be passed through a perforation 26 in the wall 27 of an outlet-box or other electrical device, represented by broken lines in Fig. 2. The device may be attached to the wall 27 of the outlet-box by means of a clamping-nut 28 applied to the stem 12, also as indicated by broken lines in Fig. 2.

When the attaching device is required to receive an electric cable of relatively-large diameter, such as the cable 29 represented by broken lines in Fig. 1, the reversible clamping-member 11 will be mounted upon the body-member 10 with its relatively-large recess 21 facing toward the clamping-portion 14 of the body-member 10. Upon tightening the clamping-screws 17, the electric cable 29 will be firmly attached to the clamping-device and hence to the outlet-box 27 or other electrical device.

If, however, it is desired to clamp an electric cable 30 of relatively-small diameter, the reversible clamping-member 11 is reversed and the relatively-small recess 23 of the lug 22 is faced toward the clamping-portion 14 of the body-member 10, as indicated in Fig. 6.

In order to avoid the necessity for the complete removal of the reversible clamping-member 11 from the body-member 10 during the installation or removal of an electric cable from the 5 device, the said clamping-member 11 may be swung about the clamping-screw 17 passing through its perforation 19 into a retired position, as indicated by broken lines in Fig. 3. This swinging of the clamping-member 11 into a 10 clearance position is, as will be noted from the accompanying drawing, permitted by the notch 20.

From the foregoing, it will be seen that the electric-cable attaching device of the present 15 invention may be used to attach either large or small electric cables to an outlet-box or the like without requiring a complex structure and without sacrificing the surety of action.

The invention may be carried out in other 20 specific ways than that herein set forth without departing from the spirit and essential characteristics of the invention, and the present embodiment is, therefore, to be considered in all respects as illustrative and not restrictive, and 25 all changes coming within the meaning and equivalency range of the appended claims are intended to be embraced therein.

I claim:

1. An electric-cable attaching device, comprising a body-member having a clamping-portion; an independently-formed reversible clamping-member carried by and movable with respect to the clamping-portion of the said body-member, the said clamping-member having two 30 cable-receiving sockets, one of which sockets is larger than the other and either of which may be faced toward the clamping-portion of the said body-member; and means for forcing the selected cable-receiving socket of the said reversible clamping-member toward the clamping-portion of the said body-member.

2. An electric-cable attaching device, comprising a body-member having a clamping-portion; an independently-formed reversible clamping-member carried by and movable with respect 45 to the clamping-portion of the said body-member, the said clamping-member having two cable-receiving sockets, one of which sockets is larger than the other and either of which may be faced toward the clamping-portion of the said body-member; and a pair of spaced-apart clamping-screws extending between the said body-member and the said reversible clamping-member and serving to force the selected cable-receiving 50 socket of the latter toward the clamping-portion of the said body-member.

3. An electric-cable attaching device, comprising a body-member having a clamping-portion; an independently-formed reversible clamping-member carried by and movable with respect to the clamping-portion of the said body-member, the said clamping-member having a cable-receiving socket in each of two of its faces, one of the said cable-receiving sockets being 60 larger than the other and either of which may be faced toward the clamping-portion of the 65

said body-member; and means for forcing the selected cable-receiving socket of the said reversible clamping-member toward the clamping-portion of the said body-member.

4. An electric-cable attaching device, comprising a body-member having a clamping-portion; an independently-formed reversible clamping-member carried by and movable with respect to the clamping-portion of the said body-member, the said clamping-member having a cable-receiving socket in each of two of its faces, one of the said cable-receiving sockets being larger 10 than the other and either of which may be faced toward the clamping-portion of the said body-member; and a pair of clamping-screws extending through the said reversible clamping-member and the clamping-portion of the said body-member to force the selected cable-receiving socket of the said clamping-member toward the clamping-portion of the said body-member.

5. An electric-cable attaching device, comprising a body-member having a clamping-portion; an independently-formed reversible clamping-member carried by and movable with respect to the clamping-portion of the said body-member, the said clamping-member having two notch-like cable-receiving sockets, one of which said notch-like sockets is larger than the other and either of which may be faced toward the clamping-portion of the said body-member; and means for forcing the selected notch-like cable-receiving socket of the said reversible clamping-member toward the clamping-portion of the said body-member.

6. An electric-cable attaching device comprising a body-member having a clamping-portion and an independently-formed reversible clamping-member carried by and movable with respect to the said body-member and having an offsetting-lug, the said clamping-member having two 40 cable-receiving sockets respectively of different sizes, one being formed in the said offsetting-lug and the other being formed in the face of the clamping-member opposite the said lug; and means for forcing the selected cable-receiving 45 socket of the said reversible clamping-member toward the clamping-portion of the said body-member.

7. An electric-cable attaching device comprising a body-member having a clamping-portion and an independently-formed reversible clamping-member carried by and movable with respect to the said body-member and having an offsetting-lug, the said clamping-member having two cable-receiving sockets respectively of different 50 sizes, one being formed in the said offsetting-lug and the other being formed in the face of the clamping-member opposite the said lug; and a pair of clamping-screws extending through the said reversible clamping-member and the clamping-portion of the said body-member to force the selected cable-receiving socket of the said clamping-member toward the clamping-portion of the said body-member.

PETER M. PETRIE.
